UNITED STATES PATENT OFFICE.

BENJAMIN JOSEPH JOHN GOULDING, OF LONDON, ENGLAND, ASSIGNOR, BY MESNE ASSIGNMENTS, TO THE AUTOPLATE COMPANY OF AMERICA, OF JERSEY CITY, NEW JERSEY, A CORPORATION OF NEW JERSEY.

APPARATUS FOR SHAVING CURVED STEREOGRAPHIC-PLATES.

1,109,831.

Specification of Letters Patent.

Patented Sept. 8, 1914.

Application filed August 9, 1909, Serial No. 511,943. Renewed February 19, 1914. Serial No. 819,841.

To all whom it may concern:

Be it known that I, BENJAMIN JOSEPH JOHN GOULDING, a subject of the King of the United Kingdom of Great Britain and 5 Ireland, residing at 188 Fleet street, in the city of London, England, have invented new and useful Improvements in Apparatus for Shaving Curved Stereotype-Plates, of which the following is a specification.

10 In automatic machines such as the auto-plate and the auto-shaver, the knife is always revolving, and the closeness to the shaving arch, of the fixed adjacent parts, as well as the transit through the machine, 15 of the procession of stereotype plates, makes it practically impossible to get at the knife. Now, it is necessary to get at the knife for the purpose of adjusting it radially, and the circumstances under which this radial ad- 20 justment is necessary, are as follows: If all stereotype plates were letter press plates throughout, they would obviously re- 25 quire trimming to one standard thickness, and no radial adjustment of the knife, once set, would be required. But, at the present 30 day, all stereotype plates are not letter press throughout, for many of them are partly letter press and partly process block. Now, the surface of a process block must, to se- 35 cure a good impression, stand a little higher than must the surface of the letter press. As a stereotype plate stands with its print- 40 ing face to the shaving arch and its oppo- 45 site or inner face to the knife, it follows that the high parts of this printing face will be the base from which its radial thick- 50 ness will be measured for the purpose of shaving. Let it be assumed that the projec- 55 tion of the process block above the letter press is three thousandths of an inch, which it generally is, then for a stereotype plate that has any or all process block work in it, the knife must be retracted for the three thousandths of an inch, in order that the 60 process surface may be left three thou- 65 sandths of an inch higher than the letter press surface.

The object of the present invention is to provide means whereby the knife may be 70 readily adjusted for trimming the two above-named kinds of plates no matter whether the plates reach the shaving apparatus in batches of one kind or the other, or whether plates of the said two kinds are

presented to the apparatus in alternation, 55 or otherwise.

The invention will be best understood by reference to the accompanying drawings which are to be taken as part of this specification and read therewith, and in which:— 60

Figure 1 is a sectional elevation of suffi- 65 cient of a shaving apparatus to show the present improvements therein; Fig. 2 is an end elevation as seen from the left-hand end of Fig. 1; Figs. 3 and 4 are sections taken 70 respectively on the lines 3—3 and 4—4 of Fig. 1, Fig. 4 showing an alternative form of knife-controlling spring; Figs. 5 and 6 are end elevations showing the knife-ad- 75 justing means in positions respectively cor- 80 responding with the knife projected and knife retracted, and Figs. 7 and 8 are elevations, taken from positions at right angles to each other, showing devices for manually adjusting the knife.

A designates the arch or plate holder in which the curved plate, which is to be shaved or trued out on its inner side, is clamped and held.

According to this invention, the knife 1 is 80 held to the knife arm 2 in such a manner as to leave it (the knife) free to be adjusted radially or approximately radially inward and outward relatively to the axis of rotation of the said knife arm. For this pur- 85 pose the knife 1 is secured to the knife arm 2 by means of a keeper plate 3 and a series of shouldered screws 4, the latter of which pass through and nicely fit holes in the keeper plate 3, and also through slots 5 90 in the knife 1 (see particularly Fig. 4) which slots admit of the knife being moved independently of the screws 4. Between the heads of the screws 4 and the proximate 95 face of the keeper plate 3, springs 6 are provided, these being adapted to hold the knife firmly between the plate 3 and knife arm 2 while, at the same time, allowing it to be moved radially, as later described. On the back of the knife 1 there is secured a 100 rib 7 (see particularly Fig. 3) engaging with a sliding fit in a groove 8 in the proximate face of the knife arm 2, this rib and groove serving to guide the knife in its radial movement.

The under or non-cutting edge of the knife 1 is formed with two or more wedge or inclined surfaces 9, (three are shown in

the drawings, see Fig. 1) with each of which there engages a correspondingly inclined surface 10 formed on a longitudinally adjustable wedge bar 11 which is supported and free to slide on blocks 12 adjustably secured, as by bolts 13 and set screws 14, to the knife arm 2. At one of its ends, the wedge bar 11 is adapted to bear against a left-handed screw 15 free to turn in a relatively fixed nut or bearing 16 fast to the knife arm 2, the outer end of the said screw having fast to it a tumbler 17, 17^a adapted to be turned in opposite directions, to two terminal positions, shown respectively in Figs. 5 and 6, the limit of motion in these directions being determined by stop pins 18, 18^a fast to the knife arm 2.

In the space between the inner ends of the two blocks 12 there is located a spring 19 whose respectively opposite ends are attached to hooks 20 and 21, the former fast to the knife arm 2, and the latter fast to the wedge bar 11, this spring serving to hold the wedge bar in constant operative contact with the screw 15.

In a block 22 fast to, or integral with, the knife arm 2, there are secured the vertical arms of two coiled springs 23 whose other or horizontal arms 24, as shown best in Fig. 3, pass through slots 25 in the keeper plate 3 and engage with holes in the knife 1, these springs serving to hold the wedge surfaces 9 of the knife 1, in constant operative contact with the corresponding surfaces 10 of the wedge bar 11.

By the foregoing arrangement it will be seen that when the screw 15 and wedge bar 11 occupy their respective left-most positions in which they are shown in Fig. 1, the knife 1 will be at the minimum distance from its axis of rotation, being held in that position by the springs 23, and when they occupy their other respective terminal positions (the right-most as viewed in Fig. 1) the knife 1 will be at the maximum distance from the said axis of rotation. The tumbler 17, 17^a is in pivotal connection with one end of a toggle link or rod 26 whose other end is free to slide in a guide 27 capable of oscillating about its axis in an arm 28 fast to the knife arm 2, the said axis of oscillation being so situated relatively to the axis of the screw 15, that when the tumbler is in its respectively opposite terminal positions, the link 26 will be at respectively opposite sides of an imaginary inclined plane containing both of the said axes. The link 26 is encircled by a compression spring 29 which serves to hold the tumbler in each of its two terminal positions, until it is positively moved from that position to the other one, as hereinafter described.

When the shaving apparatus is supplied from two casting plants, one turning out let-

plates having some process surface in them, means are provided by which the operator can make the said apparatus adjust the radial position of the knife 1 according to the plate next to be shaved. These means are as follows: There is fast to the screw 15, the before-mentioned tumbler 17, 17^a, and, pivoted at 30 upon the machine frame, (see particularly Fig. 2), there is a bell-crank lever 31, 32, the arm 31 of which carries a pin or abutment device 33 adapted to be engaged by the tumbler 17, 17^a. The other arm 32 of the bell-crank lever is connected by a link 34 to a hand lever 35 pivoted at 36 to a fixed quadrant 37 having three notches 38, 39 and 40, the hand lever 35 being capable of being locked to the quadrant 37 by a locking bolt 41 whose upper end is adapted, under the influence of a spring 42 to engage with the just mentioned notches 38, 39 and 40. When the bolt 41 is engaged with the notch 38, as indicated in Fig. 2, the pin 33 is held clear of the path of the tumbler 17, 17^a, no matter in which of its two positions it may be at the time; when the bolt 41 is engaged with the notch 39, the pin 33 is in the position in which it is marked 33^a in Fig. 2, so that at the next ensuing rotation of the knife arm 2, the said pin will be engaged by the arm 17 of the tumbler (which latter would then be in the knife-retracting position in which it is shown in Figs. 2 and 5); by this engagement the said tumbler will be turned from the last-named position to the knife-protruding position, in which it is stopped by the pin 18^a, and the wedge bar 11 will consequently be moved so as to effect the said protrusion of the knife. When the bolt 41 is engaged with the notch 40 and the pin 33 is consequently held in the position in which it is marked 33^b in Fig. 2, the said pin will be engaged by the tumbler arm 17^a so that the said tumbler will be turned to the knife-retracting position, and the wedge bar 11, through the spring 19 will be correspondingly moved to allow the knife 1 to be retracted by its springs 23.

In applying this invention to a hand shaving box, the tumbler 17, 17^a, and all the parts marked 18, 18^a and 26 to 42 both inclusive, are, as shown in Figs. 7 and 8, replaced by a hand wheel 43 either duly scaled as at 44 to coöperate with a fixed index 45, or indented to coöperate with a spring detent or its equivalent.

Among the modifications of which the before described apparatus is susceptible, there may be mentioned the employment of helical springs 46, see Fig. 4, instead of the coiled springs 23 shown in Figs. 1, 2, 3 and 8, for drawing the knife 1, inward, these helical springs (of which there may be any desired number) being attached at one end, to the knife arm 2, and at the other end, 130

to pins 47 fast to the knife, and projecting through slots or recesses in the keeper plate 3; by this arrangement the necessity for providing the before described spring-supporting block 22 is removed.

5 The screw 15 has been herein referred to as a left-handed one, and it is of this character only by reason of the pin or abutment 33 being located in the positions 33^a, 33^b for 10 moving the knife respectively outward and inward, if, however, the positions 33^a and 33^b be regarded as the knife-retracting and knife-projecting positions respectively then, obviously, the screw 15 would have a right-hand thread; it will be readily seen that 15 this question of direction of thread has no connection with the hand-rotated screw shown in Figs. 7 and 8.

I claim:—

20 1. In an apparatus for shaving stereotype printing plates, the combination of an arch, a shaving knife, and means for simultaneously and equally adjusting the ends of the knife to different determined points for different thicknesses of plates.

25 2. In an apparatus for shaving stereotype printing plates, the combination of an arch, a shaving knife, and means extending outside the arch for adjusting the knife to different determined points for different thicknesses of plates.

30 3. In an apparatus for shaving stereotype printing plates, the combination of an arch, a knife supporting arm therein, a shaving 35 knife arranged on the arm, means in the arch for adjusting the knife on the arm to different determined points for different thicknesses of plates, and means outside the arch for operating the adjusting means.

40 4. In an apparatus for shaving stereotype printing plates, the combination of an arch, a knife arm therein, a rotatable shaving knife mounted on the arm, means for adjusting the knife on the arm to different determined points for different thicknesses of plates, and means whereby the different 45 adjustments of the knife will be made by the rotation of the parts.

45 5. In an apparatus for shaving stereotype plates, the combination of an arch, a knife arm therein, a rotatable shaving knife mounted on the arm, means for adjusting the knife on the arm to different determined points for different thicknesses of plates, 50 and means which can be thrown into and out of the path of the adjusting means so that the knife can be adjusted to its different determined points by the rotation of the parts.

60 6. In an apparatus for shaving stereotype printing plates, the combination of an arch, a rotatable shaving knife therein, means whereby the shaving knife can be adjusted to different determined points for different thicknesses of plates, a tumbler on the adjusting means, and means which can be

thrown into and out of position to engage the tumbler.

7. In an apparatus for shaving stereotype printing plates, the combination of an arch, a knife arm therein, a blade radially movable on said knife arm, a keeper plate engaging the blade, screws threaded into the knife arm and passing through slots in the knife and holes in the keeper plate, 70 springs arranged under the heads of said screws, wedge surfaces arranged on the knife, a sliding wedge bar mounted on the knife arm, blocks on the knife arm for supporting the wedge bar, and means for adjusting the wedge bar.

8. In apparatus for shaving curved stereotype plates, the combination of a shaving knife, a knife arm adapted to rotate about a fixed axis, means adapted to secure the knife to the knife arm with a capacity for movement thereon nearer to and farther from its axis of rotation, wedge surfaces on the knife, a longitudinally adjustable wedge bar, wedge surfaces on the wedge bar adapted to coöperate with those on the knife, 85 a screw in operative connection with the wedge bar and adapted to adjust it longitudinally in one direction and a spring also in operative connection with the wedge bar and adapted to adjust it longitudinally in 90 the reverse direction.

9. In apparatus for shaving curved stereotype plates, the combination of a shaving knife, a knife arm adapted to rotate about a fixed axis, means adapted to secure the 100 knife to the knife arm with a capacity for movement thereon nearer to and farther from its axis of rotation, wedge surfaces on the knife, a longitudinally adjustable wedge bar, wedge surfaces on the wedge bar 105 adapted to coöperate with those on the knife, a screw in operative connection with the wedge bar and adapted to adjust it in a longitudinal direction, a tumbler fast to the screw, an abutment device adjustable on the 110 frame of the machine, and means operatively connected with the abutment device whereby it can be moved into and out of the path of the tumbler.

10. In apparatus for shaving curved stereotype plates, the combination of a shaving knife, a knife arm adapted to rotate about a fixed axis, means adapted to secure the knife to the knife arm with a capacity for movement thereon nearer to and farther 120 from its axis of rotation, wedge surfaces on the knife, a longitudinally adjustable wedge bar, wedge surfaces on the wedge bar adapted to coöperate with those on the knife, a screw in operative connection with the 125 wedge bar and adapted to adjust it longitudinally in one direction, a spring also in operative connection with the wedge bar and adapted to adjust it longitudinally in the reverse direction, a tumbler fast to the screw, 130

an abutment device adjustable on the frame of the machine, and means operatively connected with the abutment device whereby it can be moved into and out of the path of the tumbler.

11. In apparatus for shaving curved stereotype plates, the combination of a shaving knife, a knife arm adapted to rotate about a fixed axis, means adapted to secure the knife to the knife arm with a capacity for movement thereon nearer to and farther from its axis of rotation, wedge surfaces on the knife, a longitudinally adjustable wedge bar, wedge surfaces on the wedge bar adapted to coöperate with those on the knife, a screw in operative connection with the wedge bar and adapted to adjust it in a longitudinal direction, a tumbler fast to the screw, an abutment device adjustable on the frame of the machine, a lever adapted to turn about a fixed pivot and operatively connected with the abutment device whereby the latter can be moved into and out of the path of the tumbler, and a locking device adapted to retain the abutment device either out of the said path or in such path so as to engage either end of the tumbler.

12. In apparatus for shaving curved stereotype plates, the combination of a shaving knife, a knife arm adapted to rotate about a fixed axis, means adapted to secure the knife to the knife arm with a capacity for movement thereon nearer to and farther from its axis of rotation, wedge surfaces on the knife, a longitudinally adjustable wedge bar, wedge surfaces on the wedge bar adapted to coöperate with those on the knife, a screw in operative connection with the wedge bar and adapted to adjust it in a longitudinal direction, a tumbler fast to the screw, an abutment device adjustable on the frame of the machine, means operatively connected with the abutment device whereby it can be moved into and out of the path of the tumbler, and means adapted to retain the tumbler in either of its terminal positions until it is positively moved therefrom by contacting with the abutment device.

13. In apparatus for shaving curved stereotype plates, the combination of a shaving knife, a knife arm adapted to rotate about a fixed axis, means adapted to secure the knife to the knife arm with a capacity for movement thereon nearer to and farther from its axis of rotation, wedge surfaces on the knife, a longitudinally adjustable wedge bar, wedge surfaces on the wedge bar adapted to coöperate with those on the knife, a screw in operative connection with the wedge bar and adapted to adjust it longitudinally in one direction, a spring also in operative connection with the wedge bar and adapted to adjust it longitudinally in the reverse direction, a tumbler fast to the screw, an abutment device adjustable on the frame of the

machine, means operatively connected with the abutment device whereby it can be moved into and out of the path of the tumbler, and means adapted to retain the tumbler in either of its terminal positions until it is positively moved therefrom by contacting with the abutment device.

14. In apparatus for shaving curved stereotype plates, the combination of a shaving knife, a knife arm adapted to rotate about a fixed axis, means adapted to secure the knife to the knife arm with a capacity for movement thereon nearer to and farther from its axis of rotation, wedge surfaces on the knife, a longitudinally adjustable wedge bar, wedge surfaces on the wedge bar adapted to coöperate with those on the knife, a screw in operative connection with the wedge bar and adapted to adjust it in a longitudinal direction, a tumbler fast to the screw, an abutment device adjustable on the frame of the machine, means adapted to retain the tumbler in either of its terminal positions until it is positively moved therefrom by contacting with the abutment device, a lever adapted to turn about a fixed pivot and operatively connected with the abutment device whereby the latter can be moved into and out of the path of the tumbler, and a locking device adapted to retain the abutment device either out of the said path or in such path so as to engage either end of the tumbler.

15. In apparatus for shaving curved stereotype plates, the combination of a shaving knife, a knife arm adapted to rotate about a fixed axis, means adapted to secure the knife to the knife arm with a capacity for movement thereon nearer to and farther from its axis of rotation, wedge surfaces on the knife, a longitudinally adjustable wedge bar, wedge surfaces on the wedge bar adapted to coöperate with those on the knife, a screw in operative connection with the wedge bar and adapted to adjust it in a longitudinal direction, a tumbler fast to the screw, an abutment device adjustable on the frame of the machine, means operatively connected with the abutment device whereby it can be moved into and out of the path of the tumbler, a rod pivoted to the tumbler, a guide through which the said rod is longitudinally movable, and a spring on the rod adapted to retain the tumbler in either of its terminal positions until it is positively moved therefrom by contacting with the abutment device.

16. In apparatus for shaving curved stereotype plates, the combination of a shaving knife, a knife arm adapted to rotate about a fixed axis, means adapted to secure the knife to the knife arm with a capacity for movement thereon nearer to and farther from its axis of rotation, wedge surfaces on the knife, a longitudinally adjustable wedge

bar, wedge surfaces on the wedge bar adapted to coöperate with those on the knife, a screw in operative connection with the wedge bar and adapted to adjust it longitudinally in one direction, a spring also in operative connection with the wedge bar and adapted to adjust it longitudinally in the reverse direction, a tumbler fast to the screw, an abutment device adjustable on the frame of the machine, means operatively connected with the abutment device whereby it can be moved into and out of the path of the tumbler, a rod pivoted to the tumbler, a guide through which the said rod is longitudinally movable, and a spring on the rod adapted to retain the tumbler in either of its terminal positions until it is positively moved therefrom by contacting with the abutment device.

20 17. In an apparatus for shaving curved stereotype plates, the combination of a shaving knife, a knife arm adapted to rotate about a fixed axis, means adapted to secure the knife to the knife arm with a capacity for movement thereon nearer to and farther from its axis of rotation, wedge surfaces on the knife, a longitudinally adjustable wedge

bar, wedge surfaces on the wedge bar adapted to coöperate with those on the knife, a screw in operative connection with the wedge bar and adapted to adjust it in a longitudinal direction, a tumbler fast to the screw, an abutment device adjustable on the frame of the machine, a rod pivoted to the tumbler, a guide through which the said rod is longitudinally movable, a spring on the rod adapted to retain the tumbler in either of its terminal positions until it is positively moved therefrom by contacting with the abutment device, a lever adapted to turn about a fixed pivot and operatively connected with the abutment device whereby the latter can be moved into and out of the path of the tumbler, and a locking device adapted to retain the abutment device either out of the said path or in such path so as to engage either end of the tumbler.

25 In witness whereof I have hereunto set my hand in the presence of two witnesses.

BENJAMIN JOSEPH JOHN GOULDING.
